Primary Examiner — Mojtaba Tehrani(74) *Attorney, Agent, or Firm* — Luedeka Neely, P.C.; Robert Fox(57) **CLAIM**

The ornamental design for a muzzle brake, as shown and described.

DESCRIPTION

FIG. 1 is a perspective view of a muzzle brake of my new design.

FIG. 2 is a front view thereof;

FIG. 3 is a rear view thereof;

FIG. 4 is a right side view thereof;

FIG. 5 is a left side view thereof.

FIG. 6 is a top view thereof; and,

FIG. 7 is a bottom view thereof.

The broken lines in the drawings are included for the purpose of illustrating unclaimed features and form no part of the claimed design.

1 Claim, 4 Drawing Sheets(56)
